(57) **CLAIM**

The ornamental design for a shoe tensioning device, as shown and described.

DESCRIPTION

FIG. 1 is a top, left, and front perspective view of an ornamental design for a shoe tensioning device;

FIG. 2 is a front elevational view of the shoe tensioning device of FIG. 1;

FIG. 3 is a rear elevational view of the shoe tensioning device of FIG. 1;

FIG. 4 is a right side elevational view of the shoe tensioning device of FIG. 1;

FIG. 5 is a left side elevational view of the shoe tensioning device of FIG. 1;

FIG. 6 is a top plan view of the shoe tensioning device of FIG. 1; and,

FIG. 7 is a bottom plan view of the shoe tensioning device of FIG. 1.

The dash-dot-dot lines are included for the purpose of illustrating portions of the shoe tensioning device that form no part of the claimed design. The dash-dot-dot broken lines depict boundary lines and form no part of the claimed design.
